CLASP RECEIVING UNIT FOR GARMENTS

Henry M. Herbener, Thomasville, Ga.

Application June 5, 1947, Serial No. 752,644

7 Claims. (Cl. 2—336)

1

My invention relates to apparel and has particular reference to means for attaching hose supporters or the like to a garment, such as an elastic girdle.

Important objects of the invention are to improve the construction shown in my patent for Attaching means for apparel element, 2,300,154, October 27, 1942; to provide holding units which may be arranged at any selected points on the garment; to provide supporting or bearing surfaces formed of lines of stitching rather than woven webs; to provide a construction which is cheaper and more attractive in appearance; to provide a construction which renders itself to modern production methods; and to provide a construction which may be employed to reinforce seams at the edge of the garment.

Other objects and advantages of the invention will be apparent during the course of the following description.

In the accompanying drawings forming a part of this application and in which like numerals are employed to designate like parts throughout the same,

Figure 1 is a perspective view of an elastic girdle having my clasp receiving units applied thereto,

Figure 2 is a side elevation of one clasp receiving unit,

Figure 3 is a similar view, with the fabric section or patch omitted, for the purpose of illustration,

Figure 4 is a vertical section taken on line 4—4 of Figure 2,

Figure 5 is a similar view taken on line 5—5 of Figure 2,

Figure 6 is a bottom plan view of the clasp receiving unit or pocket,

Figure 7 is a side elevation, viewed from the inner face of the girdle of a slightly modified form of clasp receiving unit or pocket,

Figure 8 is an exploded perspective view of the modified form of clasp receiving unit shown in Figure 7,

Figure 9 is a plan view of a blank for forming a further modified form of clasp receiving unit,

Figure 10 is a similar view, showing parts of the blank cut away,

Figure 11 is an edge elevation of the blank partly folded,

Figure 12 is a side elevation of the same, showing the blank partly folded.

Figure 13 is a side elevation of the partly folded blank showing the same partly applied to the lower edge of the girdle.

2

Figure 14 is a side elevation of the completely folded blank completely applied to the girdle, showing the completed clasp receiving unit,

Figure 15 is a plan view of the partly folded blank as shown in Figure 13, the girdle being shown in section,

Figure 16 is a horizontal section taken on line 16—16 of Figure 14,

Figure 17 is a bottom plan view of the clasp receiving unit or pocket, showing the same folded for the insertion of the clasp,

Figure 18 is a vertical section taken on line 18—18 of Figure 14,

Figure 19 is a similar view taken on line 19—19 of Figure 14,

Figure 20 is a side elevation of the inner fabric section or patch of a further modified clasp receiving unit, applied to the garment and stitched thereto at its lower edge,

Figure 21 is a side elevation of the last named clasp receiving unit, showing the outer fabric section or patch placed in position and stitched to the garment,

Figure 22 is a vertical section taken on line 22—22 of Figure 20,

Figure 23 is a vertical section taken on line 23—23 of Figure 21, and

Figure 24 is a side elevation of the last named clasp receiving unit, completed, and

Figure 25 is a vertical section taken on line 25—25 of Figure 24.

As clearly shown in Figure 1, the numeral 10 designates the elastic girdle shown in Figure 8 of my Patent 2,300,154, October 27, 1942. The girdle comprises a body portion having a two way vertical and horizontal stretch. This body portion includes a front panel 10' which has a one way horizontal stretch.

Arranged at the lower edge of the body portion 10 is a suitable number of clasp receiving units or pockets 11'. Each clasp receiving unit or pocket comprises a fabric section or patch 11, which is preferably substantially semi-circular and has its straight edge arranged lowermost, to be adjacent to the lower edge of the body portion 10. This fabric section or patch is preferably formed of thin elastic fabric, such as artificial silk, which has a one way horizontal stretch and a smooth inner face. The fabric section 11 is shown as arranged upon the outer face of the body portion 10, although it may be arranged upon the inner face of the girdle, if desired. The marginal edge of the fabric section 11 or patch is stitched to the body portion or girdle 10 by a line of zigzag stitching 12. The fabric section 11

forms with the body portion or girdle 10 a pocket 10^b, Figures 2 and 6, having its lower end open. The body portion or girdle 10 and fabric section or patch 11 are connected by a vertical line of stitching 13, which may be a zigzag line of stitching. The body portion or girdle 10 and fabric section or patch 11 are further connected by a rectangular line of stitching 14, forming a horizontal web or rib having an upper horizontal bearing surface 15 and vertical bearing surfaces 16. The lower horizontal side of the line of stitching 14 closes the intermediate portion of the pocket 10^b forming openings upon the opposite sides of this closed portion, Figure 6. The girdle or body portion 10 and fabric section or patch 11 are also connected by horizontal lines of stitching 17, forming horizontal bearing surfaces 18. The lines of stitching 14 and 17 are zigzag lines of stitching to permit of the horizontal stretching of the elements 10 and 11.

Each unit or pocket thus provided at the lower edge of the body portion or garment 10 is adapted for receiving a flat generally U-shaped clasp 19, from which is suspended a strap 19' of a hose supporter or the like. The clasp 19 is generally U-shaped and includes a base or end 20 carrying the hose supporter strap 19' and opposed arms 21. These arms carry inwardly projecting jaws 22, 23, and 24, having upper inclined edges 25, 26, and 27. The jaws 22 have lower horizontal bearing edges 28, to engage the horizontal bearing face or surface 15; the jaws 23 have lower horizontal bearing edges 29 to engage with the horizontal bearing surface 18; and the jaws 24 have lower horizontal bearing edges 30 to engage with the bearing surface 18. The jaws engage with the several bearing surfaces simultaneously. The jaws are arranged in transverse pairs and their ends are spaced, and the bearing surfaces 15, 16, and 18 terminate short of the opposite arms 21, forming spaces 32, whereby the connected elements 10 and 11 can be stretched horizontally, within limits.

The clasp receiving units or pockets may be suitably spaced circumferentially at the bottom of the girdle, whereby the hose supporter straps 19' may be properly located, as illustrated in Figure 1. Since the units or pockets are formed by attaching the fabric sections or patches 11 to the body portion or girdle 10, it is obvious that a desired range of adjustment for the units or pockets is obtainable, by arranging the fabric section or pockets 11 at desired points upon the body portion or girdle 10, and subsequently performing the necessary stitching.

When the unit or pocket is folded longitudinally upon the line of stitching 13, Figure 17, the clasp 19 has the ends of its arms 21 inserted into the openings of the pocket 10^b, Figure 6, upon opposite sides of the stitching 13 and 14. The arms 21 are moved into the pocket 10^b and the jaws 22, 23, and 24 will be in alignment with the spaces formed by the horizontal lines of stitching. When the unit or pocket is pulled longitudinally and flattened, the jaws will pass into the spaces and engage with the shoulders or surfaces formed by the horizontal lines of stitching. The reverse of this operation occurs when the clasp is removed.

When the body portion or girdle 10 is thin, it is preferred to reinforce the same, at the area having the lines of stitching which produce the jaw supporting surfaces. This is done by applying a one-way horizontal stretch fabric tape or strip 33 to the inner face of the body portion

or girdle 10. This strip or tape is first secured to the body portion or girdle by a zigzag line of stitching 34, which follows the marginal edge of the strip or tape. The fabric section or patch 11 is now applied to the outer face of the girdle or body portion 10. All other parts of the construction remain identical with those shown and described in connection with the first form of the invention. The same line of stitching 12 is employed and the same lines of stitching 13, 14 and 17 are employed. The lines of stitching 13, 14 and 17 pass through the reenforcing tape or strip 33.

In Figures 9 to 19 inclusive, I have shown a further modification of the invention. In these figures, the numeral 35 designates a fabric blank, which may be formed of artificial silk, and which has a one-way horizontal stretch. This blank is foldable upon longitudinal lines 36 forming a side 37 and side sections 38. The blank includes a pocket side 39 integral with the side 37 and foldable upon a transverse line 40. The side sections 38 are cut diagonally at 41, providing flaps 42, carried by the pocket side 39 and foldable upon the horizontal line 40, providing a substantially continuous folded edge at the bottom of the pocket side 39. After the cut 41 is made, the side sections 38 are cut away at 43, Figure 10, so that their edges will not overlap when folded upon the side 37, Figure 12.

The folded side 37 and side sections 38 form a two layer reenforcing strip or tape and this reenforcing strip may be applied to one face of the body portion or girdle 10, such as the inner face, and is stitched to the body portion 10 by a zigzag line of stitching 43', extending along its top and sides. This stitching 43' is effected while the pocket side 39 is flat or unfolded, Figure 13.

The pocket side 39 is now folded over the outer face of the body portion or girdle 10, Figure 14, and is secured to the body portion by a line of zigzag stitching 44, which follows the marginal edge of the pocket side. The flaps 42 are now arranged upon the inner face of the pocket side 39. A rectangular zigzag line of stitching 45 is provided, passing through elements 39, 38, and 37, and corresponding to the line of stitching 14. Horizontal lines of stitching 46 are provided, passing through the elements 39, 38, and 37, and corresponding to the horizontal lines of stitching 17. A vertical line of stitching 46' is provided, passing through elements 39, 38, and 37 and corresponding to the line of stitching 13. These various lines of stitching provide the horizontal surfaces for engagement with the jaws of the clasp 19, which is used with the unit or pocket shown in Figures 9 to 19 inclusive. The same clearance or space is provided between the ends of the supporting surfaces or shoulders formed by the stitching and the sides 21 of the clasp, to permit of the horizontal stretching of the unit or pocket. The side 37 folds over the lower edge of the body portion or girdle 10, and the pocket side 39 extends laterally beyond the side 37, forming the pocket which is open at its bottom and upon opposite sides of the element 37, as shown at 37^a, Figure 17. The clasp is inserted into and removed from the unit or pocket by folding the pocket longitudinally upon the line of stitching 46', Figure 17, so that the arms 21 may enter the openings 37^a. The jaws of the clasp will now be arranged in alignment with the spaces between the horizontal lines of stitching, and when the folded unit or pocket is pulled horizontally and straightened out, such jaws will enter the spaces 75 and engage above the horizontal stitching.

In Figures 20 to 25 inclusive, I have shown a further modification of clasp receiving unit or pocket, wherein fabric sections or patches 47 and 48 are provided, and arranged in superposed relation. The fabric section 47 is next to the body portion or girdle 10, and the edge of the fabric section 47 preferably extends beyond the edge of the fabric section 48. The lower edge of the fabric section 47 is first connected with the girdle or body portion 10 by a horizontal line of zigzag stitching 49, before the fabric section 48 is placed upon the fabric section 47. After the fabric section 48 is applied to the fabric section 47, a zigzag line of stitching 50 is made, which follows the marginal edge of fabric section 48 and extends through elements 48, 47, and 10. The fabric sections 47 and 48 form the sides of a pocket. A rectangular line of zigzag stitching 53 is made, passing through the elements 48, 47, and 10, and corresponding to the line of stitching 14, Figures 1 and 2, and horizontal lines of stitching 54, passing through elements 48, 47, and 10 and corresponding to lines of stitching 17, Figures 1 and 2, and a vertical line of stitching 55, passing through elements 48, 47, and 10, and corresponding to the line of stitching 13, Figures 1 and 2. The same clasp 19, Figures 1 and 2, is used, and the arms 21 of the clasp are passed through the openings 52' of the pocket, at the opposite sides of the line of stitching 53, and the jaws of the arms 29 are brought into engagement above the horizontal lines of stitching. The same clearance or space is provided between the bearing surfaces of the lines of stitching and the arm 21, so that the pocket or unit may be stretched horizontally within limits, the fabric sections 47 and 48 having a horizontal one-way stretch.

In connection with the first form of the invention, Figure 1, the unit or pocket may be used to reinforce the seam 10^a at the lower edge of the garment. When used for this purpose, the fabric section or patch 11 will be arranged off center with respect to the seam 10^a, Figure 1. This will enable the metal clasp to be positioned at one side of the seam 10^a and not overlap the same to avoid undue thickness. The other units or pockets may be arranged in a similar manner for the same purpose.

In view of the foregoing description, it will be seen that I have provided several forms of units or pockets for receiving a common U-shaped clasp. The same mode of operation is employed in connection with each pocket for inserting or removing the clasp.

It is to be understood that the forms of my invention herewith shown and described are to be taken as preferred examples of the same and that various changes in the shape, size, and arrangement of parts may be resorted to without departing from the spirit of my invention or the scope of the subjoined claims.

Having thus described my invention, what I claim is:

1. A garment fabric section, a separate fabric section arranged upon one face of the garment fabric section at a selected location, stitching connecting the garment fabric section and the separate fabric section and extending near the marginal edge of the separate fabric section so that such sections form a pocket having closed sides and an end, said end having openings near the closed sides, a rectangular line of stitching arranged within the pocket and connecting said sections and forming vertical and horizontal bearing edges, the end openings extending longitudinally beyond the rectangular line of stitching, substan-

tially horizontal spaced lines of stitching arranged within the pocket above the rectangular line of stitching and in general alignment therewith and forming substantially horizontal bearing edges and connecting said sections, a substantially vertical line of stitching arranged near the transverse center of the pocket and connecting said sections and extending to the substantially horizontal lines of stitching, and a generally U-shaped clasp open at its forward end and having spaced longitudinal arms for insertion through the end openings, said arms having inwardly facing lateral extensions to engage over the bearing edges.

2. A garment fabric section which is horizontally elastic, a separate fabric section which is horizontally elastic arranged upon one face of the garment fabric section near the edge of the same, stitching connecting the garment fabric section and the separate fabric section so that such sections form a pocket having sides and an end, said end having openings near the sides, a rectangular line of stitching connecting said sections and arranged within the pocket and including upper and lower horizontal zigzag lines of stitching and forming vertical and horizontal bearing edges, the end openings of the pocket extending longitudinally beyond the rectangular line of stitching, substantially horizontal spaced lines of zigzag stitching arranged above the rectangular line of stitching within the pocket and in general alignment with the rectangular line of stitching and forming horizontal bearing edges and connecting said sections, a substantially vertical line of stitching arranged within the pocket and connecting said sections and extending to the substantially horizontal lines of stitching and being disposed near the transverse center of the pocket, and a generally U-shaped clasp open at its forward end and having spaced longitudinal arms for insertion through the end openings, said arms having inwardly facing lateral extensions to engage over the bearing edges.

3. A garment fabric section, a separate fabric blank including a pocket side section and a reinforcing strip formed integral, the pocket side section being foldable transversely upon the reinforcing strip and extending laterally beyond the reinforcing strip and providing a folded edge, the reinforcing strip being disposed upon one face of the garment fabric section and the pocket side section upon the opposite face and the folded edge enclosing the free edge of the garment fabric section, a line of stitching connecting the pocket side section and the garment fabric section so that they form a pocket having sides and an open end, substantially horizontal vertically spaced lines of stitching connecting the pocket side section, garment fabric section and reinforcing strip and forming shoulders arranged within the pocket, each substantially horizontal line of stitching having its ends spaced from the first-named line of stitching and the open end of the pocket extending outwardly beyond the ends of such substantially horizontal line of stitching, and a generally U-shaped clasp open at its forward end and having spaced longitudinal arms for insertion through the opening means at the end of the pocket, said arms having inwardly facing lateral extensions to engage over the substantially horizontal lines of stitching.

4. A garment fabric section, a fabric blank including a pocket side section and a reinforcing strip which are formed integral, the pocket side section being foldable upon a transverse line over

the reinforcing strip and forming a folded edge the reinforcing strip including a side and side sections foldable upon longitudinal lines over said side, the pocket side section extending laterally beyond the folded reinforcing strip, the folded reinforcing strip being disposed upon one face of the garment fabric section and the pocket side section upon the opposite face, stitching connecting the pocket side section and the garment fabric section so that they form a pocket having sides and an open end, stitching connecting the reinforcing strip and garment fabric section, substantially horizontal vertically spaced lines of stitching arranged within the pocket and connecting the garment fabric section, the pocket side section and the reinforcing strip, each substantially horizontal line of stitching having its ends spaced from the first-named stitching, and a generally U-shaped clasp open at its forward end and having spaced longitudinal arms for insertion through the opening means at the end of the pocket, said arms having inwardly facing lateral extensions to engage over the substantially horizontal lines of stitching.

5. A garment fabric section, a fabric blank including a pocket side section and a reinforcing strip which are formed integral, the pocket side section being foldable upon a transverse line over the reinforcing strip and forming a folded edge, the pocket side section having flaps foldable transversely over the pocket side section to provide folded edges, the pocket side section extending laterally beyond the reinforcing strip, the reinforcing strip including a side and side sections folded upon longitudinal lines over said side, the folded reinforcing strip being disposed upon one face of the garment fabric section and the pocket side section upon the opposite face, stitching connecting the pocket side section and the garment fabric section so that they form a pocket having sides and an open end, stitching connecting the reinforcing strip and garment section, substantially horizontal vertically spaced lines of stitching arranged within the pocket and connecting the garment fabric section, the pocket side section and the reinforcing strip, each substantially horizontal line of stitching having its ends spaced from the first-named stitching and a generally U-shaped clasp open at its forward end and having spaced longitudinal arms for insertion through the opening means at the end of the pocket, said arms having inwardly facing lateral extensions to engage over the substantially horizontal lines of stitching.

6. A garment including a fabric body portion having a free edge, a separate fabric patch arranged upon one face of the body portion at a selected position and overlapping the body portion throughout the major portion of the area of the patch and having its free edge adjacent to the free edge of the body portion, stitching securing the patch to the fabric body portion and forming a pocket having its open end adjacent to the free edges of the fabric body portion and patch, the patch and body portion forming opposite faces of the pocket, a group of stitches connecting the body portion and patch and arranged near the center of the pocket, the stitches in the group being spaced longitudinally of the group and forming shoulders within the pocket, and a generally U-shaped clasp open at its forward end and including spaced longitudinal arms for insertion into the open end of the pocket, said arms having inwardly facing lateral extensions to engage over the shoulders.

7. A garment including a flexible sheet, a separate patch arranged upon the face of the sheet at a selected position, means securing the patch to the sheet and forming a pocket having an open end, the patch and sheet forming opposite faces of the pocket, means connecting the patch and sheet and forming a group of spaced shoulders arranged within the pocket, and a generally U-shaped clasp open at its forward end and including spaced longitudinal arms for insertion within the open end of the pocket, said arms having inwardly facing lateral extension to engage over the shoulders.

35 HENRY M. HERBENER.
